US00D743384S

(12) **United States Design Patent**
Podduturi(10) **Patent No.:** **US D743,384 S**
(45) **Date of Patent:** **** Nov. 17, 2015**(54) **ANTENNA AND RADIO MODULE FOR
WATER METER**(71) Applicant: **World Products, LLC**, Sonoma, CA
(US)(72) Inventor: **Bharadvaj R. Podduturi**, American
Canyon, CA (US)(73) Assignee: **World Products Inc.**, Sonoma, CA (US)(***) Term: **14 Years**(21) Appl. No.: **29/476,812**(22) Filed: **Dec. 17, 2013**(51) LOC (10) Cl. **14-03**

(52) U.S. Cl.

USPC **D14/230**(58) **Field of Classification Search**USPC D14/138, 230-238, 299, 358; D12/42,

Pedersen, P.A.(57) **CLAIM**I claim the ornamental design for antenna and radio module
for water meter, as shown and described.**DESCRIPTION**FIG. 1 is a perspective view of an antenna and radio module
for water meter according to the invention.FIG. 2 is a top plan view of the antenna and radio module
for water meter depicted in FIG. 1.FIG. 3 is a bottom plan view of the antenna and radio module
for water meter depicted in FIG. 1.FIG. 4 is a side elevation view of the antenna and radio
module for water meter depicted in FIG. 1; and,FIG. 5 is an exploded perspective view of the antenna and
radio module for water meter depicted in FIG. 1.The broken lines illustrate portions of the antenna and radio
module for water meter which form no part of the claimed
invention.**1 Claim, 5 Drawing Sheets**FIG. 1

FIG. 2

FIG. 3

FIG. 4
